UNITED STATES PATENT OFFICE

MERRITT C. WEMPLE, OF ROCKFORD, ILLINOIS, ASSIGNOR TO GEO. D. ROPER CORPORATION, OF ROCKFORD, ILLINOIS, A CORPORATION OF ILLINOIS

VOLATILE LIQUID TRANSFER PUMP

Application filed January 31, 1929. Serial No. 336,453.

My invention relates to dispensers for volatile and inflammable liquids and contemplates the provision of an improved transfer pump for the handling of these liquids. Because of their volatility and inflammability these materials present a difficult problem in transportation and handling. Most communities have laws regulating their use, storage and handling, and some require them to be shipped and stored in steel barrels to reduce the hazard of fire and explosion. In many instances as, for example, in the use of lacquer thinners such as amyl acetate, ethyl acetone, xylol and the like, it is necessary to dispense the liquids in small quantities. In some cases it is desired to dispense it as used while in others it may be dispensed into small containers for subsequent use or sale. In plants where considerable quantities are used they are usually transferred from the drums to small containers or safety cans for use by individual workmen. These dispensing operations must be carried out with great care to prevent spilling the liquid or encouraging excessive evaporation from which dangerous and costly fires or explosions may result. In spite of all precautions, however, small fires will occasionally occur about the container. It is, therefore, also important to prevent such superficial fires from burning back into the container and causing more violent fires or explosions.

With these conditions in mind I have aimed to provide an improved dispensing assembly adapted to engage the opening or bung of the container from which the liquid is to be removed. This assembly includes a suction drop pipe extending to the bottom of the container, a pump, a dispensing nozzle, and a catch basin and support provided with a drain passage back to the container.

I have also aimed to provide a dispensing equipment for the dispensing of volatile liquids having a collapsible suction drop pipe whereby the equipment may be used with containers of variable depths or at different bungs of the same container as may be desired with drums or barrels.

Another object of the invention is the provision of a dispensing equipment for vola-

tile liquids having means provided for rapidly interrupting the flow of liquid when the pump is stopped. I have also aimed to provide a dispensing equipment for volatile liquids having a flexible hose discharge provided with means for automatically interrupting the flow of liquid from the hose when the pump is stopped.

Still further objects of the invention are the provision of a dispensing equipment having a catch basin, a drain passage leading back to the interior of the container and serving as a supporting member for the remainder of the equipment and a pump to draw the material from the container.

Other objects and associated advantages connected with my construction will become evident to those skilled in the art from the description and drawings, in which—

Figure 1 shows the equipment in use on a metal drum or barrel. The barrel is shown in section, and a portion of the suction drop pipe is broken away to show the construction of the collapsible pipe;

Fig. 2 is a fragmentary view of a modification of my invention to containers having small openings or bungs, showing the supporting spider and flexible metal suction drop pipe;

Fig. 3 is a vertical section through the discharge valve;

Fig. 4 is a vertical half section through the bung fitting, the catch basin support and drain passage, the catch basin and the flexible pipe discharge valve; and

Fig. 5 is a section on the line 5—5 showing the handle in elevation.

While a large number of embodiments of my invention are possible in many of which the arrangement will depend upon the particular use, I have shown in the drawings a type intended for use in removing solvents from drums or barrels. I have found it convenient to make the assembly capable of being dismounted or assembled on the container in three unitary parts. These are the bung screw designated generally by 6, the catch basin and support designated generally by 7, and the pumping equipment comprising a suction drop pipe 8, a pump 9, a discharge or

delivery pipe 10, an automatic check valve 11 and a flexible hose 12, if desired. They are designed to be assembled on the container in the order named and disassembled in the reverse order.

The bung screw, best shown in Fig. 4, has at its lower end two terraced threaded portions designated by 13 and 14. The two different sizes of screw and thread permits the 10 same screw to be inserted in either the bung on the end or on the side of a metal drum or barrel. The number of these threaded terraces may be increased, if desired, to enable the screw to be inserted in bungs of various 15 sizes.

When the assembly is adapted for use with containers having very small bungs it has been found convenient to provide a spider 61, Fig. 2, in order to stably support the assembly.

20 The spider is equipped with an internal thread and screws over the larger threaded portion 13. A series of downwardly extending fingers 62 bear against the surface of the container to stabilize the assembly.

25 A nut portion 15 of the bung provides space for the application of a wrench in tightening the screw. Above the nut portion is a crosswise slot 16 extending nearly halfway across the bung screw. A vertical slot 17 extends

30 from the crosswise cut to the top end of the screw. A bolt 18 passes through projections 19 on the bung screw at either side of the slot 17 and is provided at one end with a lever or handle 20. It will be observed that the inside

35 diameter of the bung screw is somewhat larger than the outside diameter of the suction drop pipe. This permits the end of the catch basin support to rest between the two. When the bolt 18 is loosened the end of the catch 40 basin support, designated generally by 21, may be partially inserted in the bung screw, taking the position shown partially in section in Fig. 4. The lower part or sleeve of the catch basin end 22 slips down into the bung screw

45 and fits closely so that by a small adjustment of the handle 20 the top of the bung screw may be tightened around it making a vapor proof connection. The distance which the catch basin support may pass into the bung screw 50 is limited by the annular flange 23. The catch basin support arm extends outward just above the bung screw in order that it have a maximum stability. Above the arm is a split ring

55 portion 24 arranged in a manner similar to that at the bung having a tightening bolt 25 to draw the top of the catch basin support end closely around the suction drop pipe and form a vapor proof connection. This also 60 serves to hold the suction drop pipe at whatever level it may be placed for use, supporting the pumping and dispensing equipment. A drain passage 26 is provided in the catch basin support and extends from the catch basin into 65 the container through the bung screw by way

of a small slotted passageway 27 on the inside of the catch basin support sleeve.

The catch basin consists of two parts, namely, a bottom half 28 attached to the support by means of a bolt 38 and having a projecting portion 29 resting within the flanged end 30 of the support, and a top half 31 attached to the lower half through the hinge flanges 32 and 33 and the pin 34. A flanged opening 35 in the center of the upper half is 75 closed by a spring closure 36, except when held open by the nozzle of the dispensing hose presently to be described which it is designed to hold in order that any liquid dripping therefrom may be returned to the container. 80

The upper half of the catch basin is adapted to be raised up on the pin 34 to an open position as shown in dotted lines, Fig. 4, to permit cans to be rested upon the ribs 37 when dispensing without the hose 12. When the basin 85 is in the closed position the upper half is held to the lower half through the force of gravity alone. The two come in contact at their peripheral rims 39 and 40 which are machined on their contact faces to smoothness whereby a normally vapor proof joint is formed. However, should pressure develop in the container the upper half of the basin will be raised by such excess pressure to permit the escape of vapors. Resting in the 90 opening at the bottom of the lower half of the catch basin is a flame baffle comprising two layers of perforated sheet metal held in place by the bolt 38, the perforations in the lower disc being smaller than those in the upper disc. Because of the presence of these discs an exterior fire will not be able to work 95 backward along the drain passage into the container and only such gases as pass through the baffle will burn. In this manner explosions due to vapor mixtures above the liquid 100 in the container will be prevented. The discs also serve as a filter for liquid returning to the container.

105 The pumping equipment is adapted to be handled as a unit. The suction drop pipe is inserted in the sleeve of the catch basin support and lowered to an appropriate depth in the container. Through the bolt 25 and the split collar 24 the suction drop pipe is capable of being held at any position in the catch basin support in order that the distance between the check valve 11 and the catch basin 110 may be varied to fit the different sizes of cans and containers to be filled. In order that at all positions the suction drop pipe may reach to the bottom of the container and be capable of removing all of the liquid a collapsible section 39 is added. This is a smaller pipe made to fit closely inside the larger pipe 8 and having a packing gland 40 of the ordinary type to prevent air from being drawn in. However, where the pipe 39 would be of such a small internal diameter as to make operation 115 slow a flexible metal hose 41 may be attached 120

directly to the end of the larger suction drop pipe. This has been found advantageous when the invention has been adopted for use on containers having small bungs which necessitates a corresponding decrease in the size of all parts entering therein including the suction drop pipe.

The upper end of the suction drop pipe is attached to the suction end of a pump 9. 10 While any suitable type of pump may be used I have here shown a vane pump of the common type operated by means of a handle 42. A gooseneck 10 is attached to the discharge end of the pump and has integral therewith an offset 43 for priming the pump when necessary.

At the outer end of the gooseneck an automatic check valve shown in section in Fig. 3 is attached. This consists of outer walls having an inlet chamber 43 and an outlet chamber 44, separated by a dividing wall 45 having a circular opening 46. A check ball 47 bears against the beveled upper edge of the circular opening closing the passage between the chambers. A spring 48 between the ball and a removable cap 49 urges the ball downward against the beveled edges and serves to close the opening against a certain amount of hydrostatic pressure. This ball and spring arrangement serves to permit the liquid to be forced through the opening by the operation of the pump which increases the pressure upon the liquid sufficiently to raise the ball against the pressure of the spring. Projections 50 from the separating wall prevent the ball from being displaced laterally by the incoming liquid. A nozzle 51 which extends downward from the outer chamber, is provided with a slot 52 along most of its length to cause the meniscus of the liquid to break and the nozzle to rapidly and completely drain when the pump is stopped. Attention is directed to the fact that the floor of the outer chamber is flat permitting all of the liquid to drain rapidly through the slot in the nozzle. Thus no liquid is held in the chamber where it may subsequently form an explosive or inflammable mixture with air.

While normally the liquid is dispensed through the nozzle 51 directly into small cans placed upon the catch basin, yet it has been found convenient to provide a hose for dispensing into larger containers which are placed upon and removed from the catch basin with difficulty. Therefore, a female threaded portion 53 is provided to receive the threaded end of a flexible hose 12. The connection thus made is such that the hose may be attached and used or not as desired, the thread being little subject to damage because of its internal position. The flexible hose consists of a hose, a threaded nipple 54 at one end adapted to screw into the valve, and an automatic ball check valve and nozzle at the other end. The hose valve, best shown in Fig. 4, consists of

a nipple portion 55, a threaded member 56, having a beveled central opening attached to the nipple, a threaded sleeve portion 57 adapted to engage the threaded member, a ball 58 designed to rest against said beveled opening, 70 an end and nozzle portion 59 adapted to engage the end of the sleeve portion, and a spring 60 between said last named members bearing upon the ball and urging it forward against the beveled opening. It will be seen that as soon as the operator stops the pump the pressure against the ball will be relieved and it will immediately be urged forward by the spring stopping the opening and shutting off the flow of liquid from the hose without permitting it to drain. In this manner the dripping and spilling of the liquid is materially reduced with a resulting reduction in the fire hazard.

It will be observed that I have provided a convenient and highly fire-proof transfer pump. The pump is quickly and easily assembled on the container, as follows: the bung screw is inserted in the bung and drawn tight; the sleeve of the catch basin support is inserted in the bung screw and the split collar tightened; and the suction drop pipe is then inserted in the sleeve of the catch basin support and pushed down to the level desired, depending upon the size of cans to be filled. The split collar of the catch basin support may then be tightened to hold the suction drop pipe. When the suction drop pipe is inserted well into the drum, the smaller bottom section 39 will strike against the bottom of the container and telescope into the larger pipe as it continues to move downward. When the flexible hose is used on the suction drop pipe it will merely bend and coil up on the bottom of the container when the suction drop pipe is lowered. The collapsibility of the pipe also permits the pump to be used in either bung of a barrel or drum. When used on the side bung of a drum the pipe 39 will be forced up almost completely into the larger pipe 8. When used on the end bung of a drum the suction drop pipe will be almost completely extended.

The manner of mounting the assembly slidably and rotatably within the bung screw aids materially in the adaptability of the pump. The operator may conveniently locate the dispensing nozzle and catch basin without moving the drum. He may also rotate the catch basin without moving the dispensing nozzle, thus offsetting them for convenience in using the hose. He may alter the vertical distance between the catch basin and the dispensing nozzle to fit different sizes of containers whereby dispensing may be had with the nozzle actually within the container thereby reducing contact of liquid and air with the resulting evaporation. Attention is directed to the ease and rapidity with which these various alterations and changes may be made.

Operation of the pump will be seen to be particularly easy, safe, and economical. When the catch basin cover is raised the assembly is ready to dispense into cans and small containers. As the pump is operated the liquid is drawn up the suction drop pipe and forced over to the check ball 47 where the pressure of the liquid lifts the ball against the pressure of its spring and the liquid flows into the chamber 44, down the nozzle 51, and into the can to be filled. When the can is practically filled the operator stops the pump and immediately the ball 47 is forced down closing the passage and stopping the flow of liquid. The small amount of liquid remaining in the chamber and nozzle rapidly drains out because of the slotted construction. The few drops which may come after the can is removed are permitted to fall into the catch basin from which they flow back into the container by way of the drain passage. Should an extraneous fire occur during this process, the contents of the container are protected by the flame baffle across the drain passage which is the only opening to the container. When the flexible hose is in use the flow of liquid is stopped in like manner. While the assembly is not being operated the vapors are held completely within the circuit since both ends are closed from contact with the atmosphere. But while thus closed, any pressure which may develop in the container is automatically relieved through the catch basin cover which rests upon the basin. Should fire cause the barrel to become heated the escaping vapors will burn upon the baffle rather than be carried back into the barrel into what may be an explosive mixture.

While I have described a particular embodiment of my invention in use in a specific instance for purposes of illustration, I do not wish to be so limited. The invention contemplates broadly an assembly such as defined in some of the claims. It should be understood that various changes might be made in the construction and arrangement without departing from the spirit and scope of the invention as expressed in the appended claims.

50 **I claim:**

1. A dispenser for volatile liquids comprising a bung screw adapted to engage the bung of a container, a spider positioned upon said bung screw arranged to brace said bung screw against said container, a return drip bowl, a flame baffle positioned in said return drip bowl, a drip return arm connected thereto and mounted upon the bung screw having a drip return passage leading to the interior of the container, a liquid pump, a suction drop pipe extending into the container whereby all of the liquid may be removed therefrom, a discharge pipe attached to the discharge end of the pump, a check valve attached to said discharge pipe in a position

convenient for discharging over said return drip bowl, and a discharge nozzle attached to said check valve for directing the outgoing liquid into a container.

2. A dispenser for volatile liquids comprising a bung screw adapted to engage the bung of a container, a return drip bowl, a drip return arm connected thereto and mounted upon the bung screw having a drip return passage leading to the interior of the container, a flame baffle positioned across said drip return passage, a liquid pump, a suction drop pipe having a telescoping section whereby said pipe may be made to extend to the bottom of containers of varying depths for removing substantially all of the liquid therefrom, a discharge pipe attached to the discharge end of the pump, a check valve attached to said discharge pipe in a position convenient for discharging into said return drip bowl, and a discharge nozzle attached to said check valve for directing the outgoing liquid into a container.

3. A dispenser for volatile liquids comprising a bung screw adapted to engage the bung of a container, a return drip bowl, a drip return arm connected thereto and mounted upon the bung screw having a drip return passage leading to the interior of the container, a liquid pump, a suction drop pipe extending into the container, a discharge pipe attached to the discharge end of the pump, a check valve attached to said discharge pipe in a position convenient for discharging over said return drip bowl comprising an enclosure having an inlet and an outlet chamber, a wall separating said chambers having a circular opening, a ball positioned over said opening, and a spring bearing against said ball, and a nozzle one end of which extends into said outlet chamber, one side of said nozzle being slotted from the outer end to a point within the outer chamber but short of the end of said nozzle to cause the meniscus of the liquid to break and the liquid to flow rapidly therefrom.

4. A dispenser for volatile liquids adapted to be mounted and dismounted upon a container in three unitary sections comprising first, a bung screw, second, a return drip bowl and a drip return arm, and third, a pumping assembly, the bung screw being the supporting member in which the drip return arm and the pumping assembly are rotatably mounted and vertically adjustable which permits the distance between the discharge end of the pumping equipment and the return drip bowl to be varied.

5. A dispenser for volatile liquids comprising a bung screw adapted to engage the bung of a container, a return drip bowl, a drip return arm mounted upon the bung screw and supporting the return drip bowl having a suction pipe sleeve at one end to rest with-

- in the bung screw and about which the latter is adapted to be closely drawn, a suction drop pipe passing through the sleeve of the drip return arm and adapted to be held at variable heights therein having adjustable means to permit the end of said suction drop pipe to reach the bottom of the container regardless of the height at which it is held in the bung screw, a liquid pump the suction end of which is attached to the suction drop pipe, and a discharge pipe attached to the discharge end of the pump. 6. A dispenser as set forth in claim 5 having a check valve attached to the discharge pipe to stop the flow of liquid when the pump ceases, and a nozzle to direct the emerging liquid. 7. A dispenser for volatile liquids comprising a bung screw adapted to engage the bung of a container, a drip return arm attached thereto having a drip return passage leading to the interior of the container, a liquid pump, a suction drop pipe extending into the container, a discharge hose attached to the discharge end of the pump, a check valve attached to said discharge hose, a discharge nozzle connected to said check valve to direct the outgoing liquid, a return drip bowl including an upper and lower section, the lower section having a plane rim, an opening into said drip return passage, and a flame baffle covering said opening, the upper section having a plane rim, a centrally located opening for receiving the discharge nozzle whereby the drip may be returned to the container, and a spring closure resting against the lower side of said opening adapted to be forced open by the insertion of the nozzle and to close when said nozzle is withdrawn, the rims on said upper and lower sections being adapted to cooperate. 8. A dispenser for volatile liquids comprising a bung screw adapted to engage the bung of a container, a spider arranged to engage said bung screw and bear against said container to brace said bung screw and associated parts, a pump having a suction drop pipe slidable through the bung screw provided with a lower end adapted to rest on the bottom of the container when the pump is at different elevations, and means for securing the suction drop pipe to the bung screw at said different elevations. 9. A dispenser for volatile liquids comprising a pump having a suction drop pipe adapted to enter a container and an overhead discharge nozzle, a return drip bowl having a cover provided with an opening having a closure, and a delivery hose having a delivery nozzle insertable in said opening in the bowl cover for closing the delivery line. 10. A dispenser for volatile liquids having a bung screw adapted to engage the opening of a container, a pump having a discharge pipe and a suction drop pipe the latter being insertable through the bung screw into the container, and means for securing said suction drop pipe to said bung screw at variable elevations in a manner substantially vapor proof, and means for bracing said suction drop pipe against said container. 11. A dispenser as set forth in claim 10 having a drip return arm and a return drip bowl supported on said bung screw, and a return drip bowl cover, said return drip bowl cover being adapted to receive the end of the discharge pipe to provide therewith a closed return conduit when the discharge pipe is not in use. 12. A dispenser as set forth in claim 10 having a drip return arm provided with a drip return passage leading to the interior of the container, a return drip bowl attached thereto having a drain opening communicating with said passage, and a flame baffle located in said passage. In witness of the foregoing I affix my signature.
